ADJUSTABLE NECKLINE BLOUSE

Liuba Kutchma, New York, N. Y.

Application March 13, 1950, Serial No. 8,499

Term of patent 7 years

(Cl. D3—25)

To all whom it may concern:

Be it known that I, Liuba Kutchma, a citizen of the United States of America, residing in New York city, county of New York, and State of New York, have invented a new, original, and ornamental Design for an Adjustable Neckline Blouse, of which the following is a specification, reference being had to the accompanying drawing, forming part thereof, wherein:

I claim:

The ornamental design for an adjustable neckline blouse, substantially as shown.

LIUBA KUTCHMA.
